JEWEL CASE

Filed Jan. 3, 1928

UNITED STATES PATENT OFFICE

JOSEPH B. HOLDEN, OF CANASTOTA, NEW YORK, ASSIGNOR TO DIEMOULDING PRODUCTION COMPANY, INCORPORATED, OF CANASTOTA, NEW YORK, A CORPORATION OF NEW YORK

JEWEL CASE

Application filed January 3, 1928. Serial No. 244,297.

This invention relates to a sectional box adapted to be used more particularly as a jewel case in which opposed similar box sections are hinged to each other along one side for opening and closing movement and are provided with means for holding them in their closed position and with additional means for automatically opening them and limiting the opening movement when the holding means is released.

One of the objects is to combine the automatic opening means and limiting means in a single unit preferably in the form of a spring wire having its opposite ends substantially concealed in suitable slots in corresponding sides of the sections and tensioned to automatically urge the sections to their open positions when the holding means is released.

Another object is to conceal the larger portions of the hinge sections within the corresponding sides of the case.

A further object is to conceal the locking means mainly within the sides of the case sections opposite the hinged sides.

Other objects and uses relating to specific parts of the invention will be brought out in the following description.

In the drawings:

Figure 1 is a perspective view of a jewel case embodying the various features of my invention.

Figure 2 is an enlarged detail sectional view taken on line 2-2, Figure 1, showing more particularly the spring connections between the sections for opening the same and limiting their opening movement, portions of the section being broken away.

Figure 3 is a sectional view similar to Figure 2 except that the case sections are closed to show the compressed positions of the spring arms, portions of the case sections being also broken away.

Figures 4 and 5 are enlarged detail sectional views of opposite ends of the case taken respectively on line 4-4, and 5-5, Figure 1, except that the case sections are closed.

Figure 6 is a transverse vertical sectional view taken in the plane of line 6-6, Figure 3.

Figure 7 is an inner face view of a por-

tion of one side of the lid section of the case, showing more particularly the slot for receiving the adjacent end of the spring.

As illustrated, this jewel case comprises opposed similar box sections —1— and —1'— of bakelite or equivalent material adapted to be cast in one and the same mold while in a plastic state to form similar chambers —2— and —2'— and marginal flanges —3— and —3'— which form the walls of their respective chambers —2— and —2'—.

The box sections —1— and —1'— are preferably rectangular or square in top plan, but obviously may be made in many different forms, the section —1— constituting the main body or receptacle for jewelry or other articles while the other section —1'— may be termed the lid or cover which is hinged at —4— along one side to the corresponding side of the other section —1— so that when closed the inner faces of the flanges —3— and —3'— will meet in a plane midway between and parallel with the top and bottom of the case.

The outer faces of the rear flanges of the box sections —1— and —1'— adjacent the hinges —4— are beveled inwardly at —5— to receive the eyes or loops of the hinges mainly within the outer surfaces of said rear flanges as shown more clearly in Figure 4 to partially conceal the same and also to allow the leaves of the hinges to be embedded or cast into the adjacent flanges of both box sections during the molding of the latter thereby further concealing the major portions of the hinges and at the same time affording a more durable and permanent connection between the hinge leaves and their respective box sections.

In addition to embedding the ends of the leaves of the hinges in the rear portions of their respective flanges —3— and —3'— they may also be held in operative position by pins —6— which are passed through registering apertures in the flanges and leaves of the hinge as shown more clearly in Figure 4.

These hinged connections between the rear flanges of the box sections brings the axes of the hinge pins in the plane of the meeting edges of said sections so that when the lid is

closed the meeting edges will closely engage each other to form a substantially dust proof joint.

Suitable means is provided for holding the lid in its closed position, said means consisting, in this instance, of a flat spring —7— having one end seated in a recess —8— of corresponding width in the inner face of the central portion of the front flange —3— and secured to said front flange by a rivet —9—, Figure 5.

The other end of the spring —7— extends upwardly across and beyond the meeting faces of the sections and is movable in a recess —8'— in the inner shaft of the central portion of the front flange of the section —1'—, said recess —8'— being in vertical alinement with and corresponding to the width of the recess —8— in the section —1— so as to form a continuation thereof when the sections are closed one upon the other.

The front end —7'— of the spring —7— is tensioned to engage the front wall of the recess —8'— and is provided with an aperture —10— adapted to engage the inner rounded end —11— of a suitable keeper pin —12— which is secured to the front flange —3'— in the center line of the recess —8'—.

The upper terminal end —7'— of the spring —7— is preferably curved inwardly to automatically ride across the inner rounded end —11— of the keeper as the case sections are closed one upon the other.

The intermediate portion of the spring catch —7— in the plane of meeting edges of the case sections is deflected or bent outwardly and forwardly through registering openings —14— in the adjacent edges of the front flanges —3— and —3'— to form a finger piece or push button —13— by which the free end —7'— of the spring —7— may be forced against its own tension out of engagement with the keeper button —11— for unlocking the sections and permitting them to be opened as shown more clearly in Figure 5.

The means for automatically opening the box sections and for limiting the opening movement comprises a forwardly and rearwardly extending link —15— interposed between the box sections preferably near one side thereof and having its opposite ends seated in lengthwise slots —16— and —16'— in the adjacent flanges —3— and —3'— of the sections —1— and —1'— respectively.

One end of the spring wire link —15— is looped or coiled around and thereby attached to a pin —17— which is secured in the walls of the slot —16— transversely thereof or parallel with the axis of the hinges —4— near the rear end of said slot.

The end of the link —15— which is coiled around the pin —17— is provided with an extension —18— projecting forwardly from said pin and tensioned against the bottom of

the slot —16'— to assist in opening the section —1'— when the spring catch —7— is released from its keeper —12— as shown more clearly in Figures 2 and 3.

The other end of the link —15— is returned rearwardly to form a loop —19— and a rearwardly projecting extension —20—, which latter is spring-tensioned against the bottom of the slot —16— and is slideable along and upon said bottom as the case sections are opened and closed, the spring tension between the link —15— and its extension —20— serving also to assist in opening the sections when the spring catch —7— is released from its holding position.

A stop pin —21— is secured in the walls of the slot —16— transversely thereof and in the path of movement of the loop —19— connecting the extension —20— to the front end of the link —15— so that when the lid —1'— by the combined spring tension of the extensions —18— and —20— the loop —19— will engage the pin —21— to limit said opening movement, the distance between the loop —19— and pin —21— when the box sections are in their closed position being arranged to limit the opening movement of the lid to a plane at substantially right angles to the other section —1— as shown in Figure 2.

The stop pin —21— is spaced from the bottom of the slot —16— a sufficient distance to allow the section —20— to ride thereunder when the lid is opened thereby assuring the engagement of the loop —19— with the stop pin to limit the opening movement of the lid, it being understood that the distance between the stop pin —21— and rear end of the slot —16— will be at least equal to and slightly greater than the length of the extension —20— to allow the loop —19— to engage the stop pin when the sections are opened.

It will be observed that the link —15— and extensions —18— and —20— are formed from a single piece of spring wire and serve the double purpose of automatically opening the box sections when the spring catch —7— is tripped and also of limiting the opening movement of said sections.

It is also to be understood that the distance between the stop pin —21— and front end wall of the slot —16— is sufficient to allow the spring link —15— and its extension —20— to move forwardly in the slot when the lid is closed.

It will be noted that when the case is closed the link —15— and its extensions —18— and —20— and also the major portions of the hinges —4— and spring catch —7— are concealed within the marginal edges of the flanges of the box sections so that the exterior of the box may present a smooth and pleasing external appearance and when the box is made of bakelite as in the present instance it may be finished in different colors accord-

ing to the esthetic taste of the purchaser without extra covering.

What I claim is:—

1. In a jewel case having opposed sections hinged together along one side to open and close, a spring link interposed between said sections and having one end attached to one section and its other end provided with an extension slidable along and upon the other section as the sections are opened and tensioned to open said sections, and means cooperating with said link for limiting its sliding movement in the direction of said opening movement.
2. In a jewel case, a box having a lid hinged thereto along one side to open and close, a V-shaped spring having one arm attached to the lid and its other arm slidable along and upon the box toward and from the hinge as the lid is opened and closed, and a stop member on the box engaged by the angle of the spring as the lid is opened for limiting the opening movement of said lid.
3. A case comprising opposed box sections hinged to each other along one edge to open and close, and a spring wire link extending in the direction of said movement and having one end attached to one section and provided with an extension spring-pressed against that section, and its other end provided with a return extension slidable along and upon the other section as the sections are opened and closed, and means on said other section for engaging the return extension for limiting the opening movement of the sections.
4. A sectional case having its sections hinged together along one side to permit them to open and close, and a spring wire link having one end attached to one section and its other end provided with a resilient extension slidable along and upon the other section toward and from the hinge and tensioned to move the link toward its section-opening position.
5. A jewel case comprising similar opposed sections hinged together along one edge and having corresponding sides provided with transverse pins, an S-shaped spring having one loop engaged with one of the pins and its other loop slidable toward and from the hinge and into and out of engagement with the other pin, the free ends of said spring being tensioned against adjacent portions of their respective sections to open the same while the intermediate portion of the spring constitutes a link for limiting said opening movement.
6. A jewel case comprising opposed sections hinged to each other along their rear sides to open and close and provided with registering slots on their meeting faces, a spring link having its opposite ends seated in said slots and provided with oppositely projecting extensions tensioned against the bottoms of their respective slots for opening the

sections, said link having one end attached to the corresponding section and its other end slidable upon the other section, and means on said other section cooperating with the sliding end of the link for limiting the sliding movement of the link as the sections are opened.

In witness whereof I have hereunto set my hand this 28th day of December, 1927.

JOSEPH B. HOLDEN.
